UNITED STATES PATENT OFFICE.

JOSEF DAUBEK, OF VIENNA, AUSTRIA-HUNGARY, ASSIGNOR TO MILLS & GIBB, OF NEW YORK, N. Y.

DESIGN FOR A CURTAIN AND COVER.

SPECIFICATION forming part of Design No. 19,263, dated August 13, 1889.

Application filed July 22, 1889. Serial No. 318,327. Term of patent 3½ years.

To all whom it may concern:

Be it known that I, JOSEF DAUBEK, of Vienna, Austria-Hungary, have invented and produced a new and original Design for Curtains and Covers, of which the following is a specification, reference being had to the accompanying photograph, forming a part thereof.

The leading feature of the design consists 10 of the panel A, constituting two side and one end border, the panel B, constituting the other end border, the mottled field C, inclosed by the border, and the panel D, drawn upon the field at one end.

15 The panel A consists of a continuous floral wreath representing a series of pink and rose like flowers and interposed bunches of scroll-like leaves. The panel B consists of the representation of flowers resembling the snow-

ball connected by bunches of leaves and buds, 20 and the field C is represented as having drawn thereon rows of thistle-like flowers a , bunches a' resembling the dogwood-flower, and a fantastic floral bunch a'' approaching in general contour a crown. The field panel 25 D consists of a central fountain-like figure d and a fanciful perpendicular figure d' at each side of the same.

I claim—

A design for curtains and covers, substantially as herein shown and described, and as per attached photograph. 30
